AIR CONDITIONING APPARATUS

Matson C. Terry, New Rochelle, N. Y., assignor,
by mesne assignments, to American Radiator
& Standard Sanitary Corporation, New York,
N. Y., a corporation of Delaware

Application April 6, 1937, Serial No. 135,271

11 Claims. (Cl. 257—138)

My invention relates to air conditioning apparatus, and more particularly to the type which is adapted to be installed in a room space and which operates to condition the air in such room space.

My invention has for its general purpose or object to produce apparatus of the above type which is of improved construction and arrangement of parts.

10 A further object of my invention is to provide apparatus of the above type which is simple in construction and is highly compact, and which supplies additional moisture to the air in the room space in an effective and efficient manner.

15 The invention consists in the novel construction and combination of parts, to be more fully described hereinafter, and the novelty of which will be particularly pointed out and distinctly claimed.

20 In the accompanying drawings, to be taken as a part of this specification, I have fully and clearly illustrated a preferred embodiment of my invention, in which drawings—

Fig. 1 is a perspective view showing one preferred embodiment of my invention.

25 Fig. 2 is a longitudinal vertical section of the apparatus shown in Fig. 1, the section being taken on the line 2—2 of Fig. 3.

Fig. 3 is a transverse vertical section taken on the line 3—3 of Fig. 2.

30 Fig. 4 is a transverse vertical section taken on the line 4—4 of Fig. 3.

Fig. 5 is an enlarged fragmentary vertical section showing the humidifying conduit, the plane of the section being substantially the same as Fig. 2.

Fig. 6 is an enlarged fragmentary vertical section taken on the line 6—6 of Fig. 5.

Fig. 7 is an enlarged fragmentary horizontal section taken on the line 7—7 of Fig. 6; and

40 Fig. 8 is an enlarged fragmentary vertical section showing a modified form of condensate disposal means.

Referring now in detail to the construction illustrated, the reference numeral 10 indicates an air conditioning unit in its entirety. The unit 10 is constructed in accordance with the present invention, and is adapted to be installed in a room space, and is operable to condition the air in said space.

50 The unit 10 comprises an enclosing casing structure which is divided interiorly by spaced vertical partition walls 11 and 12 into a main or central compartment or section 13 and a pair of wing compartments or sections 14 and 15 lo-

cated, respectively, at the sides of the main or central section. The unit 10 also comprises a skirt portion 16 surrounding the lower part of the sides and front of the central section and the wing sections.

5 The central section 13 comprises a front wall 17, a top wall 18, a rear wall 19, and a bottom wall 20. Each of the wing sections 14 and 15 comprises a bottom wall 21, a top wall 22, a front wall 23, a rear wall 24 and an end wall 25. The partition 10 walls 11 and 12 serve as end walls for the main section 13 and as end walls of the wing sections 14 and 15.

In order to facilitate assembly of the unit 10 and repair and replacement of the interior working parts, the front wall 23, rear wall 24, top wall 22 and end wall 25 of each of the wing sections 14 and 15 are formed as a rigid unit which is detachably connected to the ends of the unit 13 by means of suitable bolts 30, 31 and 32, the bolts 30 serving to secure the front wall 23 to the bottom wall 21, the bolts 31 securing the end wall 25 to the bottom wall 21, and the bolts 32 securing the top wall 22 to the adjacent partition walls 11 and 12.

25 The central section 13 is provided in its top wall 18 with an inlet opening 35 which communicates with the room, and is provided with a second inlet opening 36 in the upper rear part thereof which is adapted to communicate with the outside atmosphere through a rearwardly extending horizontal duct 37. The duct 37 is adapted to extend between a window sill and the lower sash rail of a partially raised window (not shown). The duct 37 is detachably secured to the central section by bolts 38 and 39. A damper 40 is arranged within the central section 13 and is pivoted at 41 and may be moved about its pivotal axis by a pull-rod 42 to proportion the amounts of room air and fresh air flowing into the central section 13 through the inlet openings 35 and 36.

30 The top wall 18 of the central section 13 is also provided with an outlet opening 43 which communicates with the room space and is arranged adjacent and is of substantially the same size as the inlet opening 35. The inlet opening 35 and outlet 43 are covered by suitable removable grills 44 and 45, respectively.

35 The interior of the main or central section is so constructed as to provide an upright U-shaped passage 46 (see Fig. 4) which includes a downcoming leg 47 connected at its upper end to the inlet openings 35 and 36, and an upgoing leg 48 connected at its upper end with the outlet opening 43. Arranged across the downcoming 40

45 50 55

leg beneath the inlet openings 35 and 36 is a removable filter 50 which serves to remove from the air stream any solid particles in suspension therein; such, for example, as dust, dirt, pollen, etc.

Arranged immediately below the filter 50 and in the downcoming leg 47 is a cooling coil 51 consisting of a plurality of horizontally arranged pipes 52 connected by return bends 53, and a plurality of parallel fins 54 so arranged as to offer the minimum of resistance to the flow of air downward through the downcoming leg. A suitable liquid refrigerant is supplied to the cooling coil through an inlet pipe 55, the latter being adapted to be connected to the discharge side of the conventional type of motor-compressor-condenser unit (not shown). The cooling coil is also provided with an outlet or discharge pipe 56 which may be connected to the suction side 20 of such a motor-compressor-condenser unit.

Arranged in the bottom of the U-shaped passage and beneath the cooling coil 51, is a condensate-collecting pan or receptacle 57 which is provided in its bottom with a drain connection 25 58 to which a discharge pipe 59 is connected, the latter being adapted to be connected to a convenient drain pipe in the building (not shown). In Fig. 8 of the drawings, there is shown an alternative manner of removing the condensate from the receptacle 57a when the unit is not conveniently located with respect to a drain pipe. In Fig. 8, a pipe 59a connects at one end with the drain connection 58a and extends outward through the partition 11a and wing compartment 14a, and the outlet end thereof is arranged to discharge the condensate into a portable condensate receptacle 60 supported by the floor of the room and at the exterior of the unit.

Arranged in the lower part of the U-shaped passage 46 and at the downstream side of the condensate-collecting pan 57, is a blower means 61 which operates to provide a positive flow of air from the inlets 35 and 36 through the passage 46 and through the outlet 43 into the room space. For this reason, the main or central section 13 may properly be termed an air circulating compartment. The blower means 61 here shown comprises an electric motor 62 having a shaft 63 which extends out both ends thereof. A pair 50 of blower wheels 64 are secured, respectively, to the two outer ends of the motor shaft, and a pair of blower casings 65 surround, respectively, the blower wheels 64. Each of the casings 65 is provided with axial inlet openings or eyes 66 and with a vertical and radial discharge outlet 67. The motor, blower wheels, and casing are secured as a unit to a supporting plate 68, and the latter is detachably supported at its ends by the partition walls 11 and 12, respectively.

60 The upgoing leg 48 is defined partially by the blower casings 65, and partially by a pair of vertically arranged duct sections 70. The duct sections are connected, respectively, at their lower ends to the discharge outlets 67 of the blower casings, and are connected at their upper ends to a duct portion 71 which extends longitudinally across the forward part of the central section 13 and communicates at its upper end with the outlet opening 43 (see also Fig. 2). The 65 duct sections 70 are small in cross-sectional area at their lower ends where they connect, respectively, with the casings 65, and their respective cross-sectional areas increase progressively from the casings 65 upward toward the section 71.

75 The two duct sections 70 form a sound-dead-

ened air passage which absorbs air and blower noises and thereby prevents such noises from being transmitted into the room. To this end, the sections 70 are lined with suitable sound-absorbing material indicated at 72, and slabs of 5 this material extend transversely of the sections to provide splitters 73 which perform the additional function of reducing eddy currents in the air stream and of directing the flow of the air upwardly into the section 71.

Arranged above the upper ends of the two duct sections 70 and lengthwise of the section 71, is a suitable heating coil 74, which is here shown to comprise a plurality of pipes 75 connected together at their ends, and a plurality of parallel fins 76 also fixed to the pipes and arranged in the same direction as the flow of air. Any suitable heating fluid, for example, steam or hot water, may be supplied to the inlet side of the heating coil 74 by a pipe 77 in the wing section 20 15 15. A valve 78 serves to control the flow of heating fluid to the heating coil.

The apparatus so far described can be operated to perform effectively the functions of circulating air within the room space, of introducing fresh outside air into the room, of filtering the room air and fresh air, of cooling and dehumidifying the air during the hot months of the year, and of heating the air during the cold months of the year. The apparatus which performs these functions is highly compact, and is arranged within a casing structure of pleasing appearance. The apparatus is also capable of handling a relatively large amount of air for a given over-all size of unit. The cooling coil is 30 advantageously positioned in the downstream leg 47 so as to facilitate the collection of condensate. The spacing of the cooling and heating coils in the manner disclosed is advantageous from the viewpoint of safety, because if they should 35 be placed adjacent one another, and both the heating and cooling coils placed in operation at the same time, the heat from the heating coil would cause such excessive pressures in the cooling coil as to endanger the latter and the connections thereto. The usual eddy currents at the downstream side of a blower are eliminated by the splitters 73 and diverging ducts 70, and the air from the blower is therefore evenly distributed across the lower part of the heating coil to provide uniform heating of the air and so that the latter will offer a minimum of resistance to the flow of air. The cooling coil will also offer a minimum of resistance to the flow of air as it is at the upstream side of the blower.

In accordance with the present invention, I also provide an improved means for adding moisture to the air in the room space during the cold months of the year when artificial heat is required. To this end, I provide a humidifying conduit 80 which is arranged for the most part in the wing section 14 and has an open inlet end extending through an opening 81 in the partition wall 11 and into the upgoing leg 48 of the passage 46. The main body of the conduit 80 is arranged within and extends upwardly through the wing section 14 and is connected at its open upper end with the room space through a humidified air outlet opening 82 in the top wall 22. The outlet opening 82 is arranged closely adjacent the end of the outlet opening 43 in the central section 13, for a purpose which will presently appear.

The conduit 80 is here shown to be substantially L-shaped, with the short leg 84 of the L arranged 75

horizontally and a part thereof extending into the passage 46, and with the long leg 85 of the L arranged vertically in the section 14 and connected at its upper end with the room through 5 the humidified air outlet 82.

The open inlet end of the leg 84 of the conduit is so constructed and arranged that a part of the air flowing from the blower will be diverted into the conduit and will flow positively through the 10 conduit and into the room space. The inlet end of the conduit is preferably arranged at the downstream side of the blower instead of the upstream side, because the air pressure is greater at this point. The air pressure and velocity aid 15 in providing the desired flow through the conduit 80. The construction of the open inlet end of the leg 84 can be seen more clearly from an examination of Fig. 5. As shown, the outer free end of the leg 84 is cut away along a horizontal 20 plane, as indicated at 86, and the extreme outer end of the upper or remaining part 87 of the leg 84 is closed off by a suitable plate 88. This construction provides an inlet opening 89 which faces downstream and performs effectively the function 25 of diverting a portion of the air stream into and through the conduit.

Arranged within the conduit 85 is a suitable means 90 for adding moisture to the air as it flows therethrough. According to the broader aspects of my invention, this means may be of any desired type. In accordance with the more specific aspects, I prefer that the means be of the type which discharges a fine mist or spray which may be more easily evaporated in the air. To 35 this end, I provide a spray nozzle 91 which discharges a fine stream of water against an adjustable target 92 arranged thereabove. Water under pressure is supplied to the spray nozzle by means of a pipe 93. If desired, a suitable solenoid control valve 94 may be located in the pipe 93 for the purpose of controlling the operation of the spray from a remotely located switch or thermostat. A pressure-reducing valve 95 is also located in the pipe and serves to regulate the 40 pressure of the water on the spray nozzle. Below the reducing valve is located a suitable strainer 96 for removing solid particles from the water to avoid clogging the spray head, and the lower end of the strainer may be connected to any 45 suitable source of water supply by means of a supply pipe 97.

The spray 91 when operating will introduce water into the conduit 80 in an atomized form, or mist. A portion of the mist will be evaporated 50 in the air stream flowing therethrough. Most of the remaining part of the mist will be entrained in the air stream and will be carried thereby into the room space through the humidified air outlet 82. As the outlet 82 is adjacent the outlet 43, and as the upper end of the upgoing leg 85 of the conduit 80 is in the form of a nozzle 98, and as this nozzle is inclined toward the air outlet opening 43, the entrained mist or atomized water will be positively directed into the stream of 55 heated air flowing into the room space through the outlet 43; and, as a result, the mist will become quickly evaporated in the heated air. This type of construction and arrangement provides for the addition of a relatively large amount 60 of water into the atmosphere of a room space for a given size and capacity of air conditioning unit. Also, the air humidifying function is performed by apparatus which is relatively small and is compactly arranged in a small wing part 65 of the air conditioning unit. This air humidifying

apparatus does not require a separate fan motor, as a part of the main air stream is used for introducing the moisture into the room. A further advantage of the apparatus disclosed is that no moist air or fine water vapor is passed through the main part of the unit, thereby avoiding the troubles of deposit of solids on the heating coil, reduction in efficiency and longevity of the acoustic material, and rusting and corrosion of parts contacted by the moisture.

A suitable drain connection 100 is provided in the bottom of the conduit 80 which serves to conduct away to the house drain excess water from the spray. In order to prevent the back-flow of excess water from the spray into the air passage 46, a dam in the form of a plate 101 is arranged across the outer end of the lower part of the leg 84. The height of the plate is only sufficient to perform this function without interfering with the flow of air into the inlet end of the conduit.

For the purposes of facilitating manufacture, assembly and repair, the conduit 80 is conveniently divided into two detachable parts 105 and 106; the lower part 106 being arranged partially in the wing compartment or section 14 and partially in the central compartment or section 13 and being detachably secured by screws 107 to the partition wall 11, and the upper part 105 resting at its lower end on the part 106 and extending upwardly through the outlet opening 82 in the top wall 22. The spray nozzle 91 is detachably secured to the bottom wall of the part 106 by bolts 108 passing through flanges 109 forming a part of the drop elbow 110 which is a part of the pipe 93. Thus, by removing the bolts 30, 31 and 32, the unit formed by the top, front, rear and end walls of the wing compartment 14 may be quickly removed. The upper part 105 can then be lifted from the lower part 106 and any necessary repairs can be quickly made. If it is desired or necessary, the part 106 may then be quickly removed and the entire humidifying apparatus removed and the wing compartment 14 quickly reassembled. An advantage flowing from the readily detachable feature of this construction, is that it is not necessary for a customer to buy the humidifying part of the apparatus when he first buys the air conditioning unit, for the humidifying part can be quickly and easily added after the unit 10 has been installed.

What I claim and desire to secure by Letters Patent of the United States is:

1. In air conditioning apparatus of the type adapted to be installed in a room space, the combination of wall means defining a casing structure; partition means dividing said casing structure into a main compartment and a wing compartment; said main compartment having an air outlet communicating with the room space and an air inlet spaced therefrom; said wing compartment having an outlet for humidified air; means in said main compartment providing a passage for the flow of air, connecting said inlet with said first-named outlet; blower means in said passage providing for the positive flow of air therethrough; a conduit arranged within said wing compartment and having an open outlet end communicating with said humidified air outlet and having an open inlet end extending into said main compartment and said air passage at the downstream side of said blower and so arranged with respect to the direction of air flow that a part of the stream of air flowing through

the passage is diverted into the inlet end of said conduit and flows through said conduit and into the room through said humidified air outlet; and means in said conduit for adding moisture to the stream of air flowing therethrough.

2. In air conditioning apparatus of the type adapted to be installed in a room space, the combination of wall means defining a casing structure; partition means dividing said casing structure into a main compartment and a wing compartment; said main compartment having an air outlet communicating with the room space and an air inlet spaced therefrom; said wing compartment having an outlet for humidified air and arranged adjacent said first-named outlet; means in said main compartment providing a passage for the flow of air connecting said inlet with said first-named outlet; blower means in said passage providing for the positive flow of air therethrough; means in said air passage at the downstream side of said blower for heating the air flowing therethrough; a conduit arranged within said wing compartment and having an open outlet end communicating with said humidified air outlet and having an open inlet end extending into said main compartment and said air passage at the downstream side of said blower and the upstream side of said heating means, and the inlet end being so arranged with respect to the direction of air flow that a part of the stream of air flowing through the passage is diverted into the inlet end of said conduit and flows through said conduit and into the room through said humidified air outlet; and means in said conduit providing a stream of atomized water or mist whereby the air flowing through the conduit entrains and carries such mist into the room space through said humidified air outlet.

3. In air conditioning apparatus of the type adapted to be installed in a room space, the combination of wall means defining a casing structure; upright partition means arranged in said casing structure and dividing the latter into a main compartment and a wing compartment; said main compartment having an air outlet in the upper part thereof communicating with the room space and having an air inlet spaced therefrom; means in said main compartment providing an air passage connecting said inlet opening with said outlet opening, with at least a part of said air passage extending upwardly through the compartment from the lower part thereof to the air outlet in the upper part thereof; blower means arranged in said passage and providing for the positive flow of air therethrough; said wing compartment having a humidified air outlet in the upper part thereof; an L-shaped conduit arranged within said wing compartment with the free end of one leg of the L extending through the partition means and into said main compartment and said upwardly extending portion of the air passage, and with the other leg of the L extending upwardly and connecting at its upper free end with the room space through the humidified air outlet; the free end of said one leg of the L having an opening therein so arranged with respect to the direction of air flow that it faces downstream, whereby air flowing through said passage is diverted into said conduit, and such diverted part flows through the conduit positively into the room through the humidified air outlet; and means in the conduit for adding moisture to the air flowing therethrough.

4. In air conditioning apparatus of the type adapted to be installed in a room space, the combination of wall means defining a casing structure; upright partition means arranged in said casing structure and dividing the latter into a main compartment and a wing compartment; said main compartment having an air outlet in the upper part thereof communicating with the room space and having an air inlet spaced therefrom; means in said main compartment providing an air passage connecting said inlet opening with said outlet opening, with at least a part of said air passage extending upwardly through the compartment from the lower part thereof to the air outlet in the upper part thereof; blower means arranged in said passage and providing for the positive flow of air therethrough; said wing compartment having a humidified air outlet in the upper part thereof; an L-shaped conduit arranged within said wing compartment with the free end of one leg of the L extending through the partition means and into said main compartment and said upwardly extending portion of the air passage, and with the other leg of the L extending upwardly and connecting at its upper and free end with the room space through the humidified air outlet; the free end of said one leg of the L having an opening therein so arranged with respect to the direction of air flow that it faces downstream, whereby air flowing through said passage is diverted into said conduit, and such diverted part flows through the conduit positively into the room through the humidified air outlet; water spray means arranged in said conduit for adding moisture to the air flowing therethrough; and means providing a dam across the lower part of said one leg of the L so as to prevent excess water from said spray means from flowing through said one leg into the main compartment and air passage.

5. In air conditioning apparatus of the type adapted to be installed in a room space, the combination of wall means defining a casing structure; upright partition means arranged in said casing structure and dividing the latter into a main compartment and a wing compartment; said main compartment having an air outlet in the upper part thereof communicating with the room space and having an air inlet spaced therefrom; means in said main compartment providing an air passage connecting said inlet opening with said outlet opening, with at least a part of said air passage extending upwardly through the compartment from the lower part thereof to the air outlet in the upper part thereof; blower means arranged in said passage and providing for the positive flow of air therethrough; said wing compartment having a humidified air outlet in the upper part thereof, an L-shaped conduit having one leg thereof arranged substantially horizontal and extending through the partition means into the main compartment and upright part of the passage, and having its other leg arranged vertical and extending upwardly and through the humidified air outlet in the upper part of the wing compartment, the lower part of the free end of said horizontal leg being cut away to provide an inlet opening facing downstream with respect to the direction of flow of the air, and the upper part of said free end of the horizontal leg being closed at its extremity; and means for adding moisture to the air flowing through said conduit.

6. In air conditioning apparatus of the type adapted to be installed in a room space, the combination of wall means defining a casing structure; upright partition means arranged in said casing structure and dividing the latter into a main compartment and a wing compartment; said main compartment having an air outlet in the upper part thereof communicating with the room space and having an air inlet spaced therefrom; means in said main compartment providing an air passage connecting said inlet opening with said outlet opening, with at least a part of said air passage extending upwardly through the compartment from the lower part thereof to the air outlet in the upper part thereof; blower means arranged in said passage and providing for the positive flow of air therethrough; said wing compartment having a humidified air outlet in the upper part thereof; an L-shaped conduit arranged in said wing compartment and including a substantially horizontal leg extending through said partition and into said main compartment and the upwardly extending part of the air passage, and having a substantially vertical leg extending upwardly and connecting at its upper end with the humidified air outlet; the free end of said horizontal leg being cut away in the lower part thereof to provide an inlet opening facing downstream with respect to the direction of air flow; the extreme outer free end of the upper part of said horizontal leg being closed; the outer end of the lower part of said horizontal leg being closed to provide a dam; spray means arranged within said conduit; and means for draining away excess water from the horizontal leg of said conduit.
7. In air conditioning apparatus of the type adapted to be installed in a room space, the combination of wall means defining a casing structure; upright partition means arranged at one side of said casing structure and dividing the latter into a main compartment and a wing compartment; said main compartment having an air inlet in the upper part thereof and an air outlet in the upper part thereof communicating with the room space and spaced from the air inlet; means in said main compartment providing an upright U-shaped passage, including a downcoming leg connected at its upper end to said air inlet and an upgoing leg connected at its upper end to said air outlet; blower means arranged in said passage and providing for the positive flow of air through said passage; a heating coil arranged across the upper part of said upgoing leg; said wing compartment having a humidified air outlet in the upper part thereof adjacent said first-named air outlet; a conduit arranged within said wing compartment and having an open outlet end connecting with the humidified air outlet, and having an open inlet end extending through said partition means and into the upgoing leg of said passage between the blower and the heating coil, and the open inlet end being so arranged as to divert a part of the stream of air flowing through said passage into said conduit and into the room space through the humidified air outlet; and means in said conduit for adding moisture to the air as it flows therethrough.
8. In air conditioning apparatus for use in room spaces, the combination of an enclosing casing having spaced inlet and outlet openings; wall means in said casing providing a main air circulating and heating compartment connecting said inlet and outlet openings; a blower in said compartment providing for the positive flow of a stream of air therethrough from the inlet opening to the outlet opening and into the room; a heating device in the compartment and arranged across the air stream at the discharge side of the blower; and means for by-passing a portion of the air stream around the heating device and for humidifying such by-passed portion; said means comprising a conduit having an open inlet end and an open outlet end and said conduit except for its inlet end being arranged outside of said compartment and extending in the general direction of air flow through said compartment, said open inlet end being arranged within said compartment between the discharge of the blower and said heating device, and facing generally in an up-stream direction so as to provide for the diversion of a portion of the air stream thereto and for the positive flow of the diverted portion through said conduit, said open outlet end being arranged adjacent said casing outlet opening so that the diverted portion mixes with the main body of the air after the latter has passed over the heating device, and means for adding moisture to said diverted portion as it flows through said conduit.
9. In air conditioning apparatus for use in room spaces, the combination of a casing having spaced inlet and outlet openings; wall means in said casing providing a main air circulating and heating compartment connecting said inlet and said outlet openings; a blower in said compartment providing for the positive flow of air therethrough from the inlet to the outlet and into the room space; a heating device in said compartment and arranged across the air stream at the discharge side of the blower; and a unitary air-humidifying device structurally separate from said casing and compartment and operable to divert a portion of the air stream from said compartment ahead of said heating device, humidify such diverted portion and then mix the diverted and humidified portion with the main body of the air stream after the latter has passed over the heating device; said device comprising a conduit having an open inlet end and an open outlet end and so arranged that it extends in the general direction of flow of air through said compartment, the open inlet end being arranged within the compartment between the blower discharge and the heating device and facing generally in an up-stream direction, the open outlet end communicating with the main air stream after the latter has passed over the heating device, and means in said conduit for adding moisture to the air flowing therethrough.
10. In air conditioning apparatus for use in room spaces, the combination of a casing having partition means providing first and second compartments; said first compartment having spaced inlet and outlet openings; a blower in said first compartment providing a stream of air flowing therethrough from the inlet to the outlet and into the room; a heating device in said first compartment and arranged across the air stream at the discharge side of the blower; a conduit extending in the general direction of movement of the air stream and arranged in said second compartment and having an open inlet end arranged within said first compartment between the blower discharge and the heating device and facing generally in an up-stream direction so that a portion of the air stream is diverted

into and flows positively through the conduit; the conduit having an open outlet end arranged to discharge the diverted portion of the air stream into the main body of the air stream after the latter has passed over the heating device; and means in said conduit for adding moisture to said diverted portion as it flows through the conduit.

11. In air conditioning apparatus for use in room spaces, the combination of an enclosing casing having spaced inlet and outlet openings; wall means in said casing providing an air passage connecting said inlet and outlet openings; a blower in said casing providing for the flow of air through said passage from the inlet to the outlet and into the room space; a heating device arranged across the passage and in the path of the air stream at the discharge side of the blower; an L-shaped conduit separate from

said passage and arranged within said casing with the free end of one leg extending laterally into said passage and with the other leg extending in the general direction of flow of the air stream and terminating at points beyond the heating device; the free end of said one leg being open and facing generally in an up-stream direction so as to provide for the diversion of a portion of the air stream thereinto and for the positive flow of such diverted portion through 10 said conduit; the free end of said other leg being open and so arranged that the diverted portion of the air stream mixes with the main body of the air stream after the latter has passed over the heating device; and means for adding 15 moisture to said diverted portion as it flows through said conduit.

MATSON C. TERRY.
